UNITED STATES PATENT OFFICE.

ISAAC MILLER, OF CLEVELAND, OHIO.

DESIGN FOR A BOTTLE.

Application filed March 23, 1929. Serial No. 30,596. Term of patent 14 years.

To all whom it may concern:

Be it known that I, ISAAC MILLER, a citizen of the United States, residing at 6411 Central Ave., city of Cleveland, in the county of Cuyahoga and State of Ohio, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.

ISAAC MILLER.
